(57) **CLAIM**

We claim the ornamental design for a vehicle headlamp, as shown and described.

DESCRIPTION

FIG. 1 is a perspective view of a vehicle headlamp;
FIG. 2 is a left side view thereof;
FIG. 3 is a right side view thereof;
FIG. 4 is a front view thereof;
FIG. 5 is a rear view thereof;
FIG. 6 is a top view thereof;
FIG. 7 is a bottom view thereof; and,
FIG. 8 is a perspective view of the vehicle headlamp on a vehicle.

The broken lines are included for the purpose of showing environment and portions of the vehicle headlamp that form no part of the claimed design.
